[57] **CLAIM**

The ornamental design for a tool for twisting rebar wires, as shown and described.

DESCRIPTION

FIG. 1 is a perspective view of a tool for twisting rebar wires in accordance with the present invention;

FIG. 2 is a top view;

FIG. 3 is a bottom view;

FIG. 4 is a rear view;

FIG. 5 is a side view, the opposite side view being a mirror image;

FIG. 6 is a front view;

FIG. 7 is a perspective view of a second embodiment of the invention;

FIG. 8 is a top view of the second embodiment;

FIG. 9 is a bottom view of the second embodiment;

FIG. 10 is a rear view of the second embodiment;

FIG. 11 is a side view of the second embodiment, the opposite side view being a mirror image;

FIG. 12 is a front view of the second embodiment;

FIG. 13 is a perspective view of a third embodiment of the invention;

FIG. 14 is a top view of the third embodiment;

FIG. 15 is a bottom view of the third embodiment;

FIG. 16 is a rear view of the third embodiment;

FIG. 17 is a side view of the third embodiment, the opposite side view being a mirror image; and,

FIG. 18 is a front view of the third embodiment.
